C. W. MORTIMER

SELF SPACING SHINGLE

Filed March 2, 1925

Fig. 6.

Fig. 4.

Charles W. Martiner, Inventor

UNITED STATES PATENT OFFICE.

CHARLES W. MORTIMER, OF UPPER MONTCLAIR, NEW JERSEY, ASSIGNOR TO THE BARRETT COMPANY, A CORPORATION OF NEW JERSEY.

SELF-SPACING SHINGLE.

Application filed March 2, 1925. Serial No. 12,478.

This invention relates to a shingle of the variety called self-spacing and to the process of cutting such a shingle from a sheet of roofing material. The invention is adapted to the sort of shingles commonly known in the trade as manufactured shingles in which a base of felted or fibrous material is saturated with waterproofing material such as asphalt and is then coated with a coating of plastic material which subsequently has a layer of mineral wear resisting material such as crushed stone, slate or the like, applied thereto. By this invention the shingles can be cut from a sheet of roofing material without any waste and at the same time the shingles will be such that they can be very easily and readily installed with the proper spaces between shingles in horizontal rows and with the proper amount of overlap. At the same time, the danger of water passing or being blown upwardly in the spaces between the shingles and getting inside the buildings is decreased.

In carrying out this invention a sheet of roofing material is slit or cut in such a manner that shingles are produced having one or more projections and corresponding recesses along one edge, which projections serve to cause the shingles to be spaced in horizontal rows and also serve to form the upper ends of the spaces between shingles, while at the same time the projections and recesses serve to guide the user in laying the shingles with the desired amount of the individual shingles exposed to the weather.

The invention will be understood from the description in connection with the accompanying drawings in which

Fig. 1 is a plan view of a sheet of roofing material partly broken away showing how the shingles may be cut;

Fig. 2 is a similar view showing a modification;

Fig. 3 is a similar view showing another modification;

Fig. 4 is a similar view showing still another modification;

Fig. 5 is a plan view showing an individual shingle as cut from Fig. 1; and

Fig. 6 is a plan view showing how the shingles may be installed upon the roof or side of a building.

In the drawings reference character 1 indicates a sheet of roofing material sufficiently wide to form two rows of shingles A and B,

This sheet may be slit longitudinally along the central straight line 2, along the zigzag line 3 and then along the central straight line 4. The sheet is also cut transversely along the line 5 at right angles to the edges of the sheet to form shingles of the proper length. The length of the line 2 is made equal to the length of the shingle that is to be exposed to the weather when the shingle is installed and should be somewhat less than one-half the length of the shingle, line 4 being of the same length as line 2. The zigzag line 3 is such that a projection 6 (Fig. 5) of triangular shape and a recess 7 of corresponding shape and size will be formed along one edge of the shingle A. The perpendicular distance from the point of the projection 6 to the line joining lines 2 and 4 is made equal to the desired distances between shingles in horizontal rows, the projection 6 serving to guide the user in spacing the shingles the proper distance apart when the shingle is being installed.

In the modification shown in Fig. 2 the projection 6' and recess 7' are made with curved lines instead of straight lines as shown in Fig. 1, and in the modification shown in Fig. 3 the projection 6'' and recess 7'' is shown as being rectangular in shape. In the modification shown in Fig. 4, two projections 6''' and corresponding recesses 7''' are shown. It is obvious that a larger number of projections and recesses could be provided if necessary and that the same could be made with curved instead of straight lines and that these projections might be made of other shapes, such as square, hexagonal, etc., instead of being made triangular or circular or rectangular as shown. The shingles can be cut out so that the projections will not have sharp corners to become broken, by cutting the same along curved or circular lines. The straight line along the end of the projections 6''' as shown in Fig. 3 and the points of the plurality of projections 6''' as shown in Fig. 4 are useful in guiding the user in installing the shingles parallel with each other.

Instead of cutting out single shingles as above described with the projections and recesses along one edge thereof, strip shingles may be cut out of a sheet of roofing material without loss of material in a similar manner so that one end of each of the strip shingles is provided with a notch and

projection or notches and projections of the character above described. Such strip shingles may have spaced notches or slots cut along an edge thereof to form tabs which 5 will simulate individual shingles when the strips are installed or the portions of the strips that are to be exposed to the weather may be decorated or ornamented in various ways as, for example, by heating with a hot 10 implement along selected areas to bring the plastic material out through the interstices of the mineral coating; by pressing upon certain areas while the plastic material is hot and in a semi-liquid state to cause the 15 mineral material to become embedded to a greater extent; by applying small strips of material of different colors at proper intervals; by providing streaks of stone surfacing of contrasting color at intervals; or by print- 20 ing or embossing, etc. The word "shingle" as used in this specification and the claims is intended to include either a single shingle or a shingle strip having an edge modified to simulate shingles.

25 In installing the shingles, a shingle A may be placed as indicated in the lower left-hand corner of Fig. 6, with the projection 6 turned toward the right. The next shingle is laid with its left-hand straight edge 8 con- 30 tacting with the end of the projection 6 and with its own projection 6 extending to the right and so on, for a horizontal row. The shingles in a row may be the shingles A as shown in Fig. 1, or they may be the shingles 35 B shown in the same figure turned so that their projections will extend in the same direction as the projections of the other shingles in this row, or they may be a mixture of the shingles A and B, the shingles A and B 40 being duplicates of each other when one of them is turned end for end. The shingles may, however, be installed with the other ends extending downwardly so that the projections 6 would extend toward the left, but 45 this manner of installing the shingles is usually less preferable than the manner shown in Fig. 6 because the projections 6 would thereby lie farther from the exposed ends of the shingles. The next row of 50 shingles is installed with the lower end 9

thereof even with the extreme lowest point 10 of the projection 6. It will be noticed that the extreme upper portion 11 of the recess 7 of this shingle will, at the same time, come exactly even with the upper edge 12 55 of a shingle in the next underlying row or course, so that the user is guided in laying the shingles with the proper amount of overlap as well as laying them with proper distances apart in horizontal rows. The 60 shingles will, of course, be installed as usual with joints of successive rows broken. It will be observed that the projections 6 define the upper limits of the spaces between the exposed portions of shingles so as to stop 65 water from passing or being driven any considerable distance upwardly beneath one shingle and between two shingles of an underlying row.

In cutting these shingles from a sheet of 70 roofing material, a sheet of roofing material of twice or any other multiple of times the width required to make two rows of shingles, may be used, the alternate longitudinal lines, of course, being straight lines. Or the 75 shingles may be cut transversely across the sheet instead of longitudinally thereof as shown in Fig. 1. In such case the width of the sheet of roofing material is equal to the length of the desired shingles or any con- 80 venient multiple thereof.

I claim:

1. A shingle having a projection and a corresponding recess along one edge and substantially in the center thereof, one edge 85 of said recess forming a continuation of one edge of said projection, and the edges of said shingle being straight and unbroken except for said recess and projection.

2. A shingle having a projection with an 90 apex and a corresponding recess along one edge thereof on opposite sides of and im- mediately adjacent the middle point of said edge, one edge of said recess forming a 95 continuation of one edge of said projection, and the edges of said shingle being straight and unbroken except for said recess and pro- jection.

In testimony whereof I affix my signature.

CHARLES W. MORTIMER.
